(No Model.)

R. L. TEED.
ELEVATOR BRAKE.

No. 380,465.

Patented Apr. 3, 1888.

UNITED STATES PATENT OFFICE.

RALPH L. TEED, OF CHICAGO, ILLINOIS, ASSIGNOR OF ONE-HALF TO
ALEXANDER MCGUIRE, OF SAME PLACE.

ELEVATOR-BRAKE.

SPECIFICATION forming part of Letters Patent No. 380,465, dated April 3, 1888.

Application filed December 2, 1887. Serial No. 256,833. (No model.)

To all whom it may concern:

Be it known that I, RALPH L. TEED, a citizen of the United States, and residing at Chicago, in the county of Cook and State of Illinois, have invented a certain new and useful Improvement in Elevator-Brakes, which is fully set forth in the following specification, reference being had to the accompanying drawings, in which—

10 Figure I is an elevation of a mechanism embodying my invention; Fig. II, a plan view of the same; Fig. III, a detail sectional view taken on the line 2 2 of Fig. II; Fig. IV, a detail front elevation of the slide and its gripping mechanism detached; Fig. V, a detail sectional view taken on the line 11 of Fig. II; and Fig. VI a detail sectional view taken on the line 3 3 of Fig. II.

Like letters refer to like parts in all the figures of the drawings.

My invention relates to elevator-brakes, and more particularly to that class of safety-brakes depending for their operation upon any increase in the speed of the elevator's descent above a given point, so that upon such an increase, no matter from what cause, the descent of the car will be immediately and effectually checked.

My present invention is in the nature of an improvement upon the invention set forth in Letters Patent No. 375,396, granted to me December 27, 1887, and has for its object to simplify and cheapen the construction therein set forth.

35 To this end my invention consists in certain novel features, which I will now proceed to describe, and will then particularly point out in the claims.

In the drawings, A represents the top cross-beam of the elevator-car, and B the ways upon which the said car travels. The gripping-levers C and their actuating-rods D are mounted upon the cross-beam A in substantially the same manner as in my application hereinbefore referred to, so that their construction and operation need no detailed description here. The sliding rods D, however, are connected to their bearings d by means of a spline, d', (shown in dotted lines in Fig. II of the drawings,) or 50 are otherwise constructed and arranged to

prevent their rotating, while at the same time they may move freely longitudinally in the said bearings.

E represents a revoluble sleeve mounted in bearings e on the cross-beam A and threaded internally at its ends to receive the correspondingly-threaded inner ends of the sliding rods D. These threads are right and left threads, so that when the sleeve E is rotated in one direction the rods D will be thrust outward, and when rotated in the opposite direction the said rods will be drawn inward toward each other. To operate the sleeve E, I employ a rope, F, which may be wound directly around the sleeve, but which is preferably wound upon a drum, F', attached to the sleeve.

G represents a slide to which the free end of the rope F is attached, as shown at f, the said slide being mounted in a suitable bearing, G', attached to the face of the cross-beam A, in which bearing the said slide is capable of a limited vertical movement. The upper end of the slide G is bifurcated, thus forming two arms, g, upon each of which there is pivoted a gripping-lever, H. The lower ends of these levers have arranged between them a spring, H', which tends to thrust the lower ends away from each other, and there is provided at this point a latch, h, pivoted to the lower end of one of the levers H and catching over a suitable projection, h', on the lower end of the other lever, so as to hold the said levers in a position of parallelism, as shown in the drawings, against the action of the spring H'. The upper ends of the levers H are adapted in any suitable manner to grip the governor rope or cable I, the construction which I prefer for this purpose being that shown in the drawings, in which there is mounted on the upper end of each lever a gripping cam or eccentric, i, grooved to fit the rope or cable, as shown in Fig. V, and pivoted eccentrically on the lever. The governor rope or cable I is secured at its ends in any suitable manner at the top and bottom of the elevator-well, and passes around the governor-wheel J, and also around an idler, K, mounted on the car. The governor-wheel J is provided with governor-arms J', constructed, arranged, and operating substantially as in my application hereinbefore referred to.

80 85 90 95 100

to, the relative arrangement of the parts being such that the projecting end of the latch *h* is in the path of the said governor-arms when these latter are thrust out.

5 The operation of the device is as follows: During the travel of the car at an ordinary rate of speed the parts remain in the position shown in the drawings. In case, however, the speed is increased above the point at which 10 the apparatus is set to act—as, for instance, on account of any slipping of the hoisting-cable or breakage of the same—the rate of rotation of the governor-wheel *J* will be correspondingly increased, and the governor-arms 15 *J'* will be thrust outward sufficiently to come in contact with the projecting end of the latch *h*. Upon striking this latch the gripping-levers *H* will be disengaged from each other, and their lower ends will be thrust outward 20 or separated by the spring *H'*. The outward ends of the levers will thus move inward toward each other and will grip the rope *I*. In case the eccentric-wheels *i* are employed, the grip on the rope will be more effective and 25 certain by reason of the said wheels being rotated by their contact with the rope, and owing to their eccentricity the greater the tendency of rotation imparted to them the tighter will their grip be. The slide *G* thus becomes 30 connected to the rope *I*, and this latter being a fixed rope the car will move downward while the slide remains stationary, owing to its connection with the rope. This produces a motion of the slide relative to the 35 sleeve *E*, which, owing to the rope *F* connecting the two, imparts a rotary motion to the said sleeve. The rotation of the sleeve *E* forces the rods *D* outward, owing to the screw-threaded connection between the two, and this 40 outward movement of the rods *D* causes the gripping-levers *C* to grip the ways *B*, and

thereby arrest the descent of the car. It will thus be seen that after the apparatus is once set to operate at any given speed, as soon as this speed is reached the brake will at once 45 become operative and check the descent of the car.

It is obvious that various modifications in the details of construction may be made without departing from the principle of my invention, and I therefore do not wish to be understood as limiting myself strictly to the precise details hereinbefore described, and shown in the drawings.

Having thus described my invention, what I 55 claim as new, and desire to secure by Letters Patent, is—

1. In an elevator-brake, the combination, with the car and its ways, of the gripping-levers, the rods for operating said levers, provided with threaded inner ends, the revoluble sleeve correspondingly threaded, the governor-wheel and its rope or cable, and a slide mounted on the car, connected to the sleeve to operate the same and provided with gripping devices 65 to grip the governor-rope, said gripping devices being held in an inoperative position by means of a latch arranged in the path of the governor-arms when these latter are thrust outward, substantially as and for the purposes 70 specified.

2. In an elevator-brake, the combination, with the revoluble sleeve for operating the way-gripping levers, of the governor-wheel and its rope, and the slide *G*, provided with 75 gripping-levers *H*, having eccentric-wheels *i*, latch *h*, and spring *H'*, substantially as and for the purposes specified.

RALPH L. TEED.
